UNITED STATES PATENT OFFICE.

WILLIAM H. KOON, OF CHICAGO, ILLINOIS.

DESIGN FOR A POWDER-PUFF.

55,474.

Specification for Design.

Patented June 15, 1920.

Application filed June 5, 1919. Serial No. 302,074. Term of patent 7 years.

To all whom it may concern:

Be it known that I, WILLIAM H. KOON, a citizen of the United States, residing at Chicago, in the county of Cook and State of Illinois, have invented a new, original, and ornamental Design for a Powder-Puff, of which the following is a specification, reference being had to the accompanying drawing, in which a perspective view of the design is shown.

Fig. 2 is an edge view thereof.

I claim:—

The ornamental design for a powder puff, as shown.

In testimony whereof I affix my signature.

WILLIAM H. KOON.
